Des. 221,116
Patented July 6, 1971

221,116

HEATER HOUSING FOR HAIR CURLERS OR SIMILAR ARTICLE

Henry J. Talge, Kansas City, and Marvin W. Litman,
Prairie Village, Kans., assignors to The Songrand
Corporation

Filed Mar. 31, 1970, Ser. No. 22,143

Term of patent 14 years

Int. Cl. D28—03

U.S. Cl. D86—10

Fig. 1.

Fig. 2.

Fig. 3.

Fig. 4.

Fig. 5.

FIG. 1 is a top plan view of a heater housing for hair curlers showing our new design;

FIG. 2 is a bottom plan view of same;

FIG. 3 is a front elevational view of same;

FIG. 4 is a side elevational view of same, the other side being substantially the same; and

FIG. 5 is a rear elevational view of same.

We claim:

The ornamental design for a heater housing for hair curlers or similar article, as shown and described.
